UNITED STATES PATENT OFFICE.

RUCKER E. DAVIS, OF CHICAGO, ILLINOIS.

PRESSURE-GENERATOR.

1,372,121.

Specification of Letters Patent. Patented Mar. 22, 1921.

Application filed December 5, 1919. Serial No. 342,681.

To all whom it may concern:

Be it known that I, RUCKER E. DAVIS, a citizen of the United States, residing at Chicago, in the county of Cook and State of Illinois, have invented new and useful Improvements in Pressure-Generators, of which the following is a specification.

This invention relates to apparatus for generating fluid pressure suitable for use as the motive fluid of prime movers of any type, and its object is to provide a novel and improved apparatus for generating a motive fluid consisting of steam and the combustion products of a liquid fuel.

The object stated is attained by means of a combination and arrangement of parts to be hereinafter described and claimed, and in order that the same may be better understood, reference is had to the accompanying drawing forming a part of this specification.

The drawing shows an elevation of the apparatus, partly diagrammatic, and partly in section.

Referring specifically to the drawing 5 denotes a retort chamber which has its outlet arranged to discharge into a combustion chamber 6, the latter in turn, discharging into a second combustion chamber 7 which 30 discharges into a mixing chamber 8 having an outlet 9 from which the generated motive fluid is led to the engine or motor to be driven by such fluid.

In the chamber 6 is a vapor generating coil 10 which is closed at one end, and has its other end formed with an outlet nozzle 11 extending into the contracted outlet end 12 of the chamber 6 to discharge into the chamber 7.

In the chamber 7 is a water heating coil 13 similar to the coil 10, which is also closed at one end, and has its other end formed with a nozzle 14 extending into the contracted outlet end 15 of the chamber 7 to discharge into the chamber 8.

The chamber 6 is surrounded by a water jacket 16, the chamber 7 by a water jacket 17, and the chamber 8 by a water jacket 18.

From a tank or other source 19 of water supply, a connection is made by a pipe 20 with the water jacket 16. A pipe 21 connects the water jackets 16 and 18, and a pipe 22 connects the jackets 18 and 17.

The coil 13 has a connection at its rear end with the water jacket 17, as shown at 23.

It will be evident from the foregoing that the water jackets 16, 17, and 18 and the coil 13 are supplied with water from the source 19.

The wall of the retort chamber 5 has an internal fuel vaporizing passageway 24, which is spirally arranged and has a discharge orifice 25 near the outlet end of said chamber, and to the opposite, or rear end of the passageway is connected a fuel supply pipe 26 having a valve 27 and leading from a pressure fuel tank 28 supplied with air from a pump 29 through a pipe 30. The tank 28 contains a liquid fuel, and the latter is forced from the tank by an air pressure. As this is a well known expedient a further description thereof is not deemed necessary.

The air line 30 has a branch 31 discharging into the retort chamber 5, and another branch 32 discharging into a duct 33 which opens into the chamber 7, as shown at 34, and also into the outlet portion 12 of the chamber 6 as shown at 35.

A fuel pipe 36 leads from a supply tank 37, containing a liquid fuel, and discharges into the retort chamber 5, and in said pipe is a vapor generating coil 38 located in a pan 39.

In the air lines 31 and 32 are valves 40 and 41, respectively, and from the fuel line 26 a valved branch 42 extends to discharge into the coil 10.

The apparatus is started by heating the retort 5 by means of vaporized fuel issuing from the pipe 36 and discharging into the retort, the fuel being vaporized in the coil 38, it being understood that said coil is heated by igniting a suitable quantity of liquid fuel in the heating pan 39. After the retort is sufficiently heated, the pipe 36 may be removed and the opening in the retort through which it extended plugged up. The valve 27 is now opened to admit liquid fuel into the internal fuel passage 24 of the retort wall, in which it is vaporized, the vapor being discharged from the orifice 25 into the chamber 6. This vapor is lighted by a hand torch inserted into the chamber 6 after a plug 43 is removed, and after being lighted, the plug is replaced. The burning vapor in chamber 6 heats the coil 10 therein, so that when liquid fuel is admitted to said coil, by opening a valve 44 in the pipe 42, said fuel is also vaporized, and the vapor is discharged through the nozzle 11 into the chamber 7. The flames from the burning

vapor in the chamber 6 are also discharged into the chamber 7 in which they unite with the vapor discharged thereinto by the nozzle 11. The combustion taking place in the chamber 7 heats the coil 13 and the steam generated in said coil is discharged into the chamber 8 through the nozzle 14. The combustion products in the chamber 7 are also discharged into the chamber 8 where they mix with the steam discharged thereinto, and the mixed motive fluid is then led from the outlet 9 to the motor to be driven by said fluid.

Before reaching the coil 13, the water is heated in the water jackets surrounding the chambers 6, 7 and 8, and it enters the coil heated to a high degree, steam starting to form in the water jacket 17.

A pipe 45 also extends from the water jacket 17 to discharge into the retort 5, and as the water in the jacket has already been converted into steam, the latter is discharged through the retort into the chamber 6, to increase the combustion therein. The chambers 6 and 7 also receive sufficient air through the pipe 32 to support combustion.

The coils 10 and 13 gradually increase in size or cross sectional area in the direction of their discharge ends so as to provide for expansion of the vapors as they are heated. It will also be noted that the nozzles 11 and 14 are flared in the direction of their outlet ends to create pressure at the smaller ends and allow expansion at their outlets.

I claim:

1. A mixed fluid pressure generator comprising a combustion chamber, a liquid fuel vaporizing pipe in said chamber, a second combustion chamber into which the first mentioned combustion chamber and the vaporizing pipe discharge, a steam generating pipe in the second combustion chamber, and a mixing chamber into which the steam generating pipe and the second combustion chamber discharge.

2. A mixed fluid pressure generator comprising a combustion chamber, a liquid fuel vaporizing pipe in said chamber, a second combustion chamber into which the first mentioned combustion chamber and the vaporizing pipe discharge, a steam generator in the second combustion chamber, a mixing chamber into which the steam generator and the second combustion chamber discharge, and water jackets around the aforesaid chambers, said jackets having a connection with the steam generator.

3. A mixed fluid pressure generator com-

prising a combustion chamber, a liquid fuel vaporizing pipe in said chamber, a second combustion chamber into which the first mentioned combustion chamber and the vaporizing pipe discharge, a steam generator in the second combustion chamber, a mixing chamber into which the steam generator and the second combustion chamber discharge, and a retort in the first mentioned combustion chamber and opening thereinto, said retort having fuel vaporizing means discharging into the first mentioned combustion chamber.

4. A mixed fluid pressure generator comprising a combustion chamber, a liquid fuel vaporizing pipe in said chamber, a second combustion chamber into which the first mentioned combustion chamber and the vaporizing pipe discharge, a steam generator in the second combustion chamber, a mixing chamber into which the steam generator and the second combustion chamber discharge, a retort in the first mentioned combustion chamber and opening thereinto, said retort having fuel vaporizing means discharging into the first mentioned combustion chamber, and a starting burner for the retort.

5. A mixed fluid pressure generator comprising a combustion chamber, a liquid fuel vaporizing pipe in said chamber, a second combustion chamber into which the first mentioned combustion chamber and the vaporizing pipe discharge, a steam generator in the second combustion chamber, a mixing chamber into which the steam generator and the second combustion chamber discharge, water jackets around the aforesaid chambers, said jackets having a connection with the steam generator, and a retort in the first mentioned combustion chamber and opening thereinto, said retort having fuel vaporizing means discharging into the first mentioned combustion chamber.

6. A mixed fluid pressure generator comprising a combustion chamber, a liquid fuel vaporizing pipe in said chamber, a second combustion chamber into which the first mentioned combustion chamber and the vaporizing pipe discharge, a steam generator in the second combustion chamber, a mixing chamber into which the steam generator and the second combustion chamber discharge, and a retort in the first mentioned combustion chamber and opening thereinto, said retort having its wall formed with a fuel vaporizing passageway discharging into the first mentioned combustion chamber.

In testimony whereof I affix my signature.
RUCKER E. DAVIS.
